UNITED STATES PATENT OFFICE.

HEZEKIAH L. THOMAS, OF BALTIMORE, MARYLAND.

RAILROAD TIE.

Application filed January 31, 1924. Serial No. 689,771.

To all whom it may concern:

Be it known that I, HEZEKIAH L. THOMAS, a citizen of the United States, residing at Baltimore, State of Maryland, have invented 5 certain new and useful Improvements in Railroad Ties (Case A), of which the following is a specification.

This invention comprehends certain new and useful improvements in railroad ties, 10 particularly ties of reinforced concrete or similar composition, and the invention has for its primary object a tie of this character which will possess to a marked degree the characteristics of durability, simplicity, and 15 rigidity, so far as withstanding breaking-down strains or stresses are concerned, while at the same time it will possess sufficient resilience to produce when installed a sufficiently yielding road bed to assist materially 20 in the riding qualities of the rolling stock.

The invention also has for its object a tie of this character embodying improved means for supporting and holding the rails in place, such means including fiber or wood 25 blocks supported in recesses in the upper face of the tie underneath the rails and designed to support the rails in a resilient manner while at the same time provision is made for preventing the rail cushions from 30 mashing or otherwise breaking down, provision being made for holding the rails rigidly in place as against accidental displacement while at the same time imparting sufficient resiliency to them to absorb shocks 35 such as they are manifestly subjected to when a train passes over them.

With these and other objects in view, as will more fully appear as the description proceeds, the invention consists in certain 40 constructions, arrangements and combinations of the parts that I shall hereinafter fully describe and claim.

Reference is to be had to the accompanying drawings, in which

45 Figure 1 is a perspective view of a railroad tie embodying one form of my invention.

Fig. 2 is a longitudinal sectional view thereof.

50 Fig. 3 is a perspective view of the reinforcing portions that are embedded in the concrete of the tie.

55 Figs. 4 and 5 are fragmentary views illustrating particularly the fiber or wood cushion designed to directly support the

rail, and the manner in which said cushion is mounted in the tie.

Fig. 6 is a fragmentary side elevation illustrating another embodiment of the rail holding means or devices.

Fig. 7 illustrates in detail the form of yoke that may be used as part of the rail holding means illustrated in Fig. 6 or as part of the rail holding means illustrated in 65 Fig. 2.

Fig. 8 is a detail perspective view of the yoke employed in that form of rail holding means which is illustrated in Figs. 1 and 2, and Fig. 9 is a detail perspective view of 70 one of the reinforcing plates that are embedded in the concrete rail holding lugs of the tie.

Corresponding and like parts are referred to in the following description and designated in all of the views of the accompanying drawings by like reference numerals.

Referring to the drawings, the numeral 1 designates the body portion of the tie which is preferably molded of concrete or the like 80 and of any desired shape or contour except as hereinafter noted. The body portion 1 is formed in its upper face with recesses 2 to receive the rails and rail holding means, each recess being formed at one side with an undercut wall 3 to produce an integral rail holding lug or member 4 which is designed to extend over the outer base flange of the rail 5 and up along and in contact with the web thereof, preferably terminating short of 90 the underside of the head of the rail as best illustrated in Fig. 2. The opposite wall of each recess 2 is also undercut as at 6, to receive and engage with the outer beveled wall 7 of a rail holding block 8 formed of 95 metal, concrete or the like, said rail holding block being formed at its rail engaging side with a lug 9 corresponding to the rail holding lug 4 as clearly illustrated in the drawings.

100 Preferably the block 8 is formed in its upper face with a transversely extending groove or recess 10 to receive and hold, as against accidental displacement, the cross bar 11 of a yoke 12, said yoke being substantially of inverted U-form and being provided at the extremities of its vertically disposed members with apertured eyes 13 to receive the transversely extending bolt or rod 14 which extends through the tie 110 from side to side as shown and which is

held in place by nuts 15 or similar fastening members. In this form or embodiment of the invention now being described, the concrete body 1 of the tie is reinforced by means of a plurality of bars or plates 16, which extend longitudinally of the tie in laterally spaced relation one to another and on edge. These plates or bars 16 are foraminous, as shown, the openings extending therethrough being of any desired shape, number and arrangement; but preferably in this embodiment of the invention the reinforcing plates are in the form of steel girders formed with a middle and two-end series of triangular shaped openings 17, the third series being separated by relatively solid portions 18 formed with a plurality of round openings 19, one set of openings 19, transversely considered, registering to receive and accommodate the bolt or rod 14, and a cylindrical metal sleeve 20 which surrounds said bolt and which is embedded in the concrete along with the reinforcing members 16, thereby obviating the necessity of coring a hole for the bolt 14 and allowing said bolt to bear against the metal sleeve 20 instead of against the concrete, thereby removing the possibility of the bolt or rod chipping the concrete body of the tie.

At their ends the transversely spaced vertically disposed and longitudinally extending reinforcing plates or bars 16 are preferably joined together by means of end plates 21. These are formed at their ends with notches 22 forming lugs 23 designed to engage and interlock with corresponding lugs 24 formed on the ends of the outermost reinforcing plates or bars 16, and the end plates are formed intermediate of their ends with openings 25 through which lugs 26 of the intermediate reinforcing plates or bars pass, said lugs 26 being thereupon bent over upon the outer sides of the end plates 25 so as to produce a rigid framework composed of the reinforcing bars and their connecting end plates 21. Preferably the end plates 21 are formed with any desired number of openings 27 that are filled with concrete in the completed tie in order to assist in holding the reinforcing structure securely embedded in place.

Preferably also each concrete rail holding lug 4 is reinforced to withstand fracture by means of a curved and preferably perforated plate 28, said plate being formed of metal and provided at its ends with downwardly and inwardly turned lugs 29 engaging the top flanges 30 of the outermost reinforcing plates or bars 16, it being noted that these bars are formed at top and bottom with lateral flanges in order to assist in imparting rigidity thereto. It will be seen that these lug reinforcing plates 28 curve upwardly and inwardly through and are embedded in the rail holding lugs 4 and

that they effectively reinforce said lugs as against the fractures that might otherwise occur at these points where the rails when in position impart the greatest strain or side thrust against the tie in actual use. Preferably the reinforcing plates 28 are formed with apertures 31 of any desired size, in order that they will be better held in place by the concrete.

In order to give the rails 5 sufficient resiliency to absorb shocks such as rails are ordinarily subjected to when a train passes over them, the body 1 of the tie is formed in its upper face underneath the rails with grooves or recesses 32 extending entirely across the face of the tie from one side wall to the other, and depressions 33 are formed in these recesses, the side walls of the depressions terminating short of the side walls of the body of the tie. Fitting snugly in these depressions or pockets 33 are wood or fiber blocks or cushions 34 designed to directly support the rails and it will be at once apparent that by means of this construction and arrangement the cushions 34 will have a chance to be compressed vertically within themselves due to pressure on the rails but at the same time cannot crush out as they are retained on all sides by the side walls of the recesses 32.

In the modification illustrated in Fig. 6 of the drawings, the concrete tie body 1^a is formed in its upper face on both sides of the rails with recesses 2^a similar to the recesses 2 hereinbefore described, two rail holding blocks 8^a being here employed, one on each side of the rail and being similar to the hereinbefore described blocks 8. In this embodiment also a modified form of holding yoke 12^a is shown, said yoke comprising a cross bar 11^a designed to be seated in a transverse groove in the upper face of the block and being held in place by vertical rods 11^b apertured at their lower ends to receive the fastening rod 14^a and extending at their upper ends through apertures formed in the ends of the transverse bar 11^a, nuts 15^a screwing on the upper ends of the vertical rods 11^b and bearing against the ends of the transverse rod 11^a as shown, and the parts 11^b and 14^a being preferably held together by means of washers and cotter pins as shown. In this construction, as well as in the construction first described, the outermost lower corners of the blocks are preferably rounded somewhat as illustrated to prevent them from chipping the concrete.

From the foregoing description in connection with the accompanying drawings, the manner of formation, assembling and practical use of my improved railroad tie will be obvious. It will be seen that I have provided a very simple, durable, and efficient construction of concrete tie which

will be able to well withstand the hard usage to which devices of this kind are necessarily subjected, that the rails will be securely held in place, and at the same time

5 will be permitted to have some vertical yielding movement so as to absorb the shocks that they will be subjected to when trains pass over them.

Preferably the base or lower face of the 10 tie is formed with a substantially elliptical recess 35 relatively shallow throughout but deepest at the middle of the tie both longitudinally and transversely considered and tapering towards both the side walls and 15 the ends, the object of this recess being to assist in holding the tie securely in the ballast.

While the accompanying drawings illustrate what I believe to be the preferred embodiment of my invention, yet it is to be understood that my invention is not limited thereto and that various changes may be made in the construction, arrangements and proportions of the parts without departing 25 from the scope of the invention as claimed.

What is claimed, is:

1. A railroad tie comprising a body portion formed in its upper face with rail receiving recesses, said recesses being undercut at one side to form rail holding lugs designed to overhang and engage the bases of the rails, blocks insertible in said recesses at the opposite sides of the rails from said lugs and engageable with the bases of the 35 rails, yokes extending over and upon said blocks and down along the sides of the body of the tie, and fastening members holding the ends of said yokes to the tie for the purpose described.

40 2. A railroad tie comprising a body portion formed in its upper face with rail receiving recesses undercut at opposite sides, one of said undercuts forming a rail engaging lug designed to contact with the base 45 and web portion of a rail at one side thereof, rail holding blocks receivable in said recesses and designed to engage the opposite portions of the base and web of the rails, said blocks being formed with beveled outer 50 ends designed to fit underneath the corresponding undercut portions of the recesses, said blocks being formed in their upper faces with transverse grooves, yokes extending across said blocks and engaging in said grooves and provided with downwardly extending end portions upon the sides of the body portion of the tie, and transverse fastening members extending through and across the tie and secured to the lower extremities of the downwardly extending end portions of the yokes for the purpose described.

60 3. A railroad tie comprising a concrete body portion formed in its upper face with rail receiving recesses, said recesses being

undercut at one side to form overhanging rail engaging lugs, means for holding the rails in said recesses in engagement with said lugs, and curved and apertured reinforcing plates embedded in the concrete 70 body portion of the tie in the said lugs thereof, as and for the purpose set forth.

4. A railroad tie comprising a concrete body portion formed in its upper face with rail receiving recesses, said recesses being 75 undercut at one side to form rail engaging lugs, reinforcing plates embedded in the body portion of the tie and extending longitudinally thereof and other reinforcing plates embedded in the body portion of the 80 tie and connected to the first mentioned reinforcing plates, the second named reinforcing plates being mounted in said lugs, as and for the purpose set forth.

5. A railroad tie comprising a concrete 85 body portion formed in its upper face with rail receiving recesses, said recesses being undercut at one side to form overhanging rail engaging lugs, reinforcing plates embedded in the body portion of the tie and 90 extending longitudinally thereof, and reinforcing plates embedded in said lugs and formed at their lower ends with downwardly and inwardly turned lugs engaging with the first named plates, as and for the purpose set forth.

6. A railroad tie comprising a concrete body portion, a plurality of reinforcing members embedded in said body portion and extending longitudinally thereof, said 100 reinforcing members being formed at their ends with lugs, and end plates extending transversely in the body portion of the tie and formed with lugs interlocking with the lugs of said reinforcing members, as and 105 for the purpose set forth.

7. A railroad tie comprising a concrete body portion, a plurality of reinforcing plates embedded in said body portion and extending longitudinally thereof, said plates 110 being arranged in laterally spaced relation to each other and formed at their extremities with lugs, and end plates extending transversely along the ends of the first named plates and formed at their ends with 115 lugs interlocking with the lugs of the outermost plates of the series, the end plates being formed intermediate of their ends with openings to receive the end lugs of the intermediate reinforcing plates of the series. 120

8. A railroad tie comprising a concrete body portion, reinforcing plates embedded in said body portion and extending longitudinally thereof, the body portion being formed in its upper face with rail receiving recesses, blocks receivable in said recesses and engageable with the rails to assist in holding the same in said recesses, yokes engageable with said blocks and having end portions extending downwardly 125 130

along the side walls of the body portion, sleeves extending transversely through the body portion and the reinforcing plates, and fastening rods mounted in said sleeves and engageable at their ends with the lower extremities of the downward extending portions of the yokes.

9. A railroad tie comprising a concrete body having rail engaging lugs, a plurality of longitudinally extending reinforcing plates embedded within the body in laterally spaced relation, and upwardly extending plates embedded within said lugs and having base portions disposed upon and bridging all of said longitudinal plates.

10. A railroad tie comprising a concrete body having rail engaging lugs, a plurality of reinforcing plates embedded within the body and arranged in laterally spaced parallel relation, and upwardly extending plates embedded within the body and the lugs thereon, said last named plates having base portions disposed upon the upper edges of and bridging all of said longitudinal first named plates and secured to the outermost ones thereof. 20
25

In testimony whereof I affix my signature.

HEZEKIAH L. THOMAS.
